UNITED STATES PATENT OFFICE.

PAUL E. FLEMING, OF CHICAGO, ILLINOIS.

CARD-SPREADING DEVICE.

1,380,371.

Specification of Letters Patent. Patented June 7, 1921.

Application filed February 7, 1921. Serial No. 442,915.

To all whom it may concern:

Be it known that I, PAUL E. FLEMING, a citizen of the United States, residing at Chicago, in the county of Cook and State 5 of Illinois, have invented new and useful Improvements in Card-Spreading Devices, of which the following is a specification.

This invention relates to devices for spreading index or other file cards in file 10 cabinet drawers so that ready and quick reference may be made to said cards without raising or removing the cards from the drawers or otherwise disturbing or displacing them from the positions they occupy in 15 the drawers.

Among the objects of my invention is to provide a spreading device which will efficiently accomplish the purpose mentioned and consists in the matters hereinafter 20 described and more particularly set forth in the appended claims.

In the accompanying drawings—

Figure 1 is a perspective view of a file cabinet of the single drawer type, equipped 25 with a card spreading device of my invention;

Fig. 2 is an enlarged longitudinal, vertical sectional view, taken on line 2—2 of Fig. 1; the drawer being shown closed;

Fig. 3 is a vertical, transverse sectional view, taken on line 3—3 of Fig. 2;

Fig. 4 is a similar sectional view, taken on line 4—4 of Fig. 2;

Fig. 5 is a horizontal sectional view taken 35 on line 5—5 of Fig. 2;

Fig. 6 is a transverse sectional view taken on line 6—6 of Fig. 2;

Fig. 7 is a perspective view of the card spreading shoe;

Fig. 8 is a view showing how the shoe spreads the cards; and

Fig. 9 is a view of the shoe mounted in a manner different from that shown in the preceding figures.

In the drawings, I have shown a single card filing box 1 having a drawer 2. The drawer has side walls 3, 3, a bottom wall 4, a rear wall 5, and a front wall 6, the latter having a size to close the outer open end of the box 1 when the drawer is closed. The side walls 3 terminate short of the top of the front wall 6 to engage under cleats or strips 7, 7, secured to the side walls of the box 1 on the inside thereof and forming guides 5 for the drawer as it is moved into and out of the box. Filed in the drawer and stand-

ing substantially upright on their lower edges are a plurality of index cards 8, these being all the same size so as to extend up above the upper edges of the side walls 3 60 substantially the same distance, and the drawer 2 may be provided with a plurality of transverse wires 9 for the purpose of holding the cards upright and in segregated groups, as indicated in Fig. 2, although these 65 wires may be omitted and the usual follower employed to hold the cards substantially in contact as customary in card drawers of this general character.

The card spreading mechanism of my invention is constructed and applied to the file box as follows. Arranged above the cards in the drawer is a rod 10, which extends from the back of the box 1 to a point short of the outer open end thereof, 70 as shown in Figs. 2 and 5. This rod 10 has at its outer end an arm 11 and at its inner end an arm 12, both of which are rotatably connected with the box 1 in a manner permitting the rod to have a swinging 80 movement toward and from the top of the cards or drawer. This is accomplished by having the outer arm 11 bent and extended through a bracket 13 depending from the top of the box 1 and the other arm 12 rotatably engaged in a socketed member 14 secured to the rear wall of the box, as shown in Fig. 5.

Secured to the under side of the top of the box and extending lengthwise thereof are 90 two laterally spaced metal strips 15, 15 forming a guide-way for a flat plate or slide 16. This carries at its rear end a stop member 17 arranged beyond the rear ends of the guides 15 so as to contact therewith and 95 limit the forward movement of the plate 16 in the slide-way. This plate 16 is moved rearward while the rod 10 is rocked downward toward the cards in the drawer and moved forward by a spring, such construction to be now described.

Secured to the rear wall of the box is a bracket 18, this being high enough above the bottom wall of the box to clear the rear wall 5 of the drawer, which does not extend 105 above the side walls thereof, as shown in Fig. 6. Between this bracket 18 and the top wall of the box is a vertical shaft 19 journaled at its lower end on the bracket and at its upper end in the top wall of the box. 110 Fixed to this shaft 19 is an arm 20 having its outer end connected to the inner end of a

link 21, which has its outer end connected with an arm 22 of a cam member 23 located between the guides 15 and pivotally mounted on the plate 16 by a pivot pin 24. The pin 24 extends through an arm 25 also secured to the plate 16 and extending over the cam member 23. The cam member 23 carries a pin 26, which when brought into contact with the adjacent side edge of the arm 25 stops the rotation of the cam member and causes the plate 16 to be slid backward when the shaft 19 is rocked in a direction for that purpose. This is brought about by providing on the shaft 19 another arm 27 connected with a link 28, which has a universal joint connection with an arm 29, as shown in Figs. 5 and 6. This arm 29 is connected with the rod 10. A spring 30 is coiled about a pin on the bracket 14 and has one end fixed to the file box and the other end bearing against the rod 10 so as to normally hold the rod in position along the top of the box and the other parts in the position shown in full lines in Figs. 2 and 5.

25 The outer end of the plate 16 carries a shoe 31, which, as shown in Fig. 7, has a flat body portion 32 overlapping the plate 16 and is provided adjacent its rear end with a pair of lugs or ears 33 to enter recesses or apertures in the plate 16. Adjacent the outer end of the body portion is a strap 34, through which is inserted the free end of a leaf spring 35 for the purpose of drawing the body portion up against the plate 16 and normally holding the shoe 31 out of contact with the upper edges of the cards in the drawer 2. The inner end of this spring 35 is secured to the plate 16.

30 The drawer 2 carries a rod 36, which extends along the bottom wall of the drawer and preferably in the slot with which these drawers are usually provided. To the rear end of this rod 36 is secured an arm 37, to which is connected the lower end of a member 38 extending upward through an elongated slot in a bracket 39 secured to the rear wall 5 of the drawer and having at its upper end a hook 40 to engage over the rod 10. At the forward end of the rod 36 is secured an arm 41, and extending through the front wall 6 of the drawer adjacent its upper end is a short shaft 42 having at its inner end a crank arm 43 connected with the arm 41 by a link 44. This shaft 42 extends through the front wall of the drawer and is provided at its outer end with a handle 45.

35 The structure described operates as follows: When it is desired to inspect any one or a number of cards 8 in the drawer, without withdrawing the particular card or cards from the drawer, the latter is pulled open by grasping the handle 45. The rod 10 is held in its position up along the top of the box, as shown in Fig. 6, by the spring 30, and the hook 40 slides along the rod 10 as

the drawer 2 is pulled out without swinging the rod downward, as the handle 45 is not turned as the drawer is being slid outward. After the drawer has been opened to the point desired, that is, to that point where it is desired to spread a particular group of cards, the movement of the drawer is stopped and then the handle 45 is turned to rotate the rod 36 and draw down the hooked member 38, which rocks the rod 10 down against the action of the spring 30 and draws the plate 16 rearward, which has heretofore remained in its normal position at the front end of the guide-way between the strips 15. As the cam member 23 is turned, its forwardly projecting lug 46 is turned to ride over a raised cam projection 47 at the inner end of the shoe body 32 and causes the shoe 31 to move downward against and into contact with the upper edges of the cards. In this movement the shoe body 32 pivots about the lugs 33. The cam member 23 is caused to rotate by the link 21 pulling on it and a spring pressed pawl 48 mounted on one of the guide strips 15 engaging a lug 49 on the cam member, as shown in Fig. 5. The pawl 48 retains its engagement with the lug 49 as the plate 16 is being moved rearward and carries the shoe therewith until the curved edge 50 of the cam member 23 moves the pawl 48 out of engagement with the lug 49, whereupon the lug 46 is on the highest point of the cam 47 and holds the shoe 31 in contact with the upper edges of the cards 8 and, as the plate 16 is carried back to the limit of its rearward movement, causes the shoe 31 to remain in contact with the cards 8 and spread or separate their upper edges as the shoe moves over the tops thereof. As soon as the plate 16 reaches the limit of its rearward movement, the handle 45 is released. The spring 30 then acts to return the parts to their normal positions and the shoe 31 is instantly raised above and out of contact with the cards before the plate 16 starts forward, because the cam member 23 turns back to its normal position before the spring exerts its pressure to move the plate 16 forward. As soon as the lug 49 rides past the pawl 48, the latter snaps into position to the rear of the lug and places the parts in position to operate over again when the handle 45 is turned for that purpose.

40 By this construction, the spreading of the upper edges of the cards is controlled independently of the movement of the drawer, and thus the shoe 31 may be brought directly to bear on that particular group of cards which it is desired to spread, not being required first to spread all of the cards in advance of that group before reaching the group desired. This is an advantage because the unnecessary spreading of cards not wanted is avoided and further permits the drawer to be opened to the particular group 1

of cards to be spread and then spreading those cards without moving the drawer at all and in that way control the spreading of the cards because the operator can spread them rapidly or slowly by turning the handle 45 at the speed desired. Furthermore, if the card desired in the particular group being spread is not seen when first spread, the handle may be turned and the 10 operation repeated as many times as needed to bring the particular card or cards to view, without at any time moving the drawer and moving that group of cards away from the spreading shoe. For example, suppose that the group of cards shown in Fig. 8 contain at their upper edges, the names and addresses of customers, clients, or others whose last names all begin with the same letter of the alphabet, say 15 "F", and this group is arranged in the drawer 2 in the position occupied by that letter in the alphabet, there of course being other groups of cards for the other letters. Should it be desired that one of the cards 20 in group "F" be inspected in order to make note of the name and address of a certain person in that group, the drawer 2 is pulled out until the shoe 31 is above and at the beginning of that group. The drawer is stopped and the handle 45 then turned and the shoe caused to come down on the tops of those cards, moved over the cards rearward, bending their upper edges backward and spreading the cards in succession so that 25 the data on the upper portions thereof may be seen, without reaching in and separating the cards or removing them out of the group or from the file drawer. After the shoe 31 has moved to spread all of the cards in the 30 group, the mechanism heretofore described raises the shoe above and out of contact with the cards and returns it to its forward position at the beginning of the group without being in contact with the cards. In case it 35 is desired to again spread the cards to note the same one or others in the group, the handle 45 is again turned and the operation repeated. Should it be desired to spread a group or groups in advance or to the rear of the group "F", the drawer is moved to the group desired and the cards in that group spread in the same manner as described for the group "F". This enables the cards to be 40 inspected quickly and with ease and without removing the cards from the drawer or disturbing or displacing them.

In Fig. 7, I have shown a shoe 51 adjustably connected with its body portion 32, and this is accomplished by making the shoe 45 separate from the body part and connecting it by a screw and slot connection 52, 53, respectively, as shown. This will take care of cards of various heights that may be placed in the drawer and further permit the shoe 55 to exert the proper amount of downward

pressure on the upper ends of the cards to gain efficient spreading.

In Fig. 9, I have shown a shoe 54 fixed to the outer end of the rod 10, and omitting the plate 16 and its associated mechanism 70 heretofore described for actuating the shoe. In the arrangement shown in Fig. 9, the shoe 54, when the rod 10 is rocked downward by the handle 45, comes in contact with the upper end of the cards, and spreads the 75 cards by bending them backward as the drawer is pulled outward. In this form, the cards are spread by the movement of the drawer, the position of the shoe being fixed.

While I have shown and described herein 80 in detail a card spreading mechanism constructed and mounted in accordance with my invention, it is to be of course understood that the details of construction and arrangement of parts shown may be variously 85 changed and modified without departing from the spirit and scope of my invention.

I claim as my invention:

1. The combination with a receptacle 90 adapted to contain file cards, one behind the other and substantially upright, of a member in said receptacle and adapted while in contact with the cards to spread the same by bending their upper edges backward, in succession, in the relative movement of said 95 cards and member past each other.

2. The combination with a file cabinet 100 having a slidable drawer therein adapted to contain file cards, one behind the other and substantially upright, of a shoe in said cabinet above said cards, and means operable from the exterior of said cabinet for bringing said shoe down against the cards 105 to spread the same by bending their upper edges backward, in succession, in the relative movement of said shoe and cards past each other.

3. The combination with a file cabinet, 110 of a drawer slidably mounted therein and adapted to contain file cards, one behind the other and substantially upright, and a member in said cabinet and adapted while in contact with the cards to spread the same by bending their upper edges backward, in 115 succession, in the movement of said member independently of the movement of said drawer.

4. The combination with a file cabinet, 120 of a drawer slidably mounted therein and adapted to contain file cards, one behind the other and substantially upright, and a member located in and supported by said cabinet above the cards and adapted while in contact with the cards to spread the same by bending their upper edges backward, in 125 succession, in the movement of said member and said drawer relatively to each other.

5. The combination with a file cabinet, 130 of a drawer slidably mounted therein and adapted to contain file cards, one behind the

other and substantially upright, and a member located in and supported by said cabinet above the cards and adapted while in contact with the cards to spread the same by bending their upper edges backward, in succession, in the movement of said member independently of the movement of said drawer.

6. The combination with a file cabinet, 10 of a drawer slidably mounted therein and adapted to contain file cards, one behind the other and substantially upright, a shoe located in and supported by said cabinet above the cards, coöperating means carried 15 by the drawer and cabinet and operable from the exterior of the drawer for causing said shoe to be brought down into contact with the cards and to spread the same by bending their upper edges backward, in succession, in the movement of said shoe independently of the drawer.

7. The combination with a file cabinet, 20 of a drawer slidably mounted therein and adapted to contain file cards, one behind the other and substantially upright, a shoe located in and supported by said cabinet above the cards, and coöperating means carried by the drawer and cabinet and operable from the exterior of the drawer for causing 25 said shoe to be brought down into contact with the cards and for moving said shoe a predetermined distance over a group of said cards for spreading the same independently of the remaining cards in the 30 drawer.

8. The combination with a file cabinet, 35 of a drawer slidably mounted therein and adapted to contain file cards, one behind the other and substantially upright, a shoe located in and supported by said cabinet above the cards, coöperating means carried by the drawer and cabinet and operable from the exterior of the drawer for causing 40 said shoe to be brought down into contact with the cards and for moving said shoe a predetermined distance over a group of said cards for spreading the same independently 45 of the remaining cards in the drawer, and means for raising the shoe out of contact with the cards after the spreading operation 50 and for returning the shoe to its starting position.

9. The combination with a file cabinet having a drawer therein adapted to contain 55 file cards, one behind the other and substantially upright, of a shoe in said cabinet above said cards, means operable from the exterior of said cabinet for bringing said shoe down against the cards, means actuated 60 through said first mentioned means for moving said shoe while in contact with the cards backward over the same to spread them by bending their upper edges backward, in succession, and means for raising said shoe out 65 of contact with the cards after the spread-

ing operation and to return the shoe to its starting position above the cards.

10. The combination with a file cabinet having a drawer therein adapted to contain 70 file cards, one behind the other and substantially upright, of a shoe in said cabinet above said cards, mechanism comprising means for bringing said shoe down against the cards, means actuated through said first mentioned means for moving the shoe while 75 in contact with the cards backward over the same to spread them by bending their upper edges backward, in succession, means for raising the shoe out of contact with said cards after the spreading operation and to 80 return the shoe to its starting position above said cards, a handle carried by said drawer and operable from the outside thereof for actuating said mechanism, and means connecting said handle with said mechanism 85 in a manner permitting said handle to operate said mechanism independently of the movement of said drawer and to allow the latter to slide in the cabinet without actuating said mechanism. 90

11. The combination with a file cabinet having a drawer therein adapted to contain file cards, one behind the other and substantially upright, of a shoe in said cabinet above 95 said cards, means for bringing the shoe down against the cards for spreading the same by bending their upper edges backward, in succession, in the movement of said shoe backward over said cards while in contact therewith independently of the movement of said drawer, and a handle carried by said drawer and operable from the outside thereof for operating said shoe actuating means, said handle being connected with said means in a manner permitting the 100 drawer to be moved to bring below the shoe the group of cards to be spread thereby.

12. The combination with a file cabinet having a drawer therein adapted to contain file cards, one behind the other and substantially upright, of a shoe pivotally and slidably supported by said cabinet above said cards, a rod rockably supported by said cabinet above said cards and extending lengthwise of said drawer, means connecting the 110 shoe and rod and adapted upon the rocking of the rod toward said cards to rock the shoe down against the cards and to move the shoe backward over the cards while in contact therewith to spread the cards by bending their upper edges backward, in succession, spring means to rock the rod away from the cards when released, spring means to raise the shoe out of contact with the cards after the spreading operation and to 115 return the shoe to its starting position when the rod is released, a handle rockably mounted on the drawer and operable from the exterior thereof, and means including a hook member slidably engaged with the rod to 120

depress the same when the handle is turned in one direction.

13. The combination with a file cabinet having a drawer therein adapted to contain file cards, one behind the other and substantially upright, of an endwise movable plate slidably supported by the cabinet above the cards, a shoe pivotally connected with said plate, coöperating cam members on the plate and shoe for moving the latter into contact with the upper edges of the cards, a rod rockably supported by the cabinet above the cards and extending lengthwise of the drawer, means connecting the plate with said rod for causing the cam member to rock the shoe into contact with the cards and to slide the plate rearward to spread the cards by the shoe upon rocking the rod toward the cards, spring means to raise the shoe out of contact with the cards upon the release of the rod, spring means for returning the shoe to its starting position above the cards when the rod is released, a handle rockably mounted on the drawer and operable from the exterior thereof, and means including a hook member slidably engaged with said rod for actuating the shoe to spread the cards when the handle is turned in a direction to draw the rod down toward the cards.

14. The combination with a file cabinet having a drawer therein adapted to contain file cards, one behind the other and substantially upright, of an endwise movable plate slidably supported in the cabinet above the cards, a shoe pivotally connected with said plate, a cam member pivoted on said plate in rear of said shoe and engaging an inclined rib on said shoe, an arm secured to said cam member, a rod rockably supported in said cabinet above said cards and extending lengthwise of the drawer, mechanism connecting said rod with said arm for moving said plate back and forth in the rocking of said rod, a bar rockably mounted in said drawer below the cards and connected with said rod in a manner permitting the drawer to be slid in said cabinet without rocking said rod, a handle rotatably mounted at the front of said drawer and operable from the exterior thereof, means connecting said han-

dle with the rod for rocking the same in a direction to spread the cards by said shoe, and spring means for the shoe and rod for raising the shoe out of contact with the cards and returning the shoe and rod back to starting position upon releasing said handle to turn in the opposite direction.

15. The combination with a file cabinet having a drawer therein adapted to contain file cards, one behind the other and substantially upright, of a shoe in said cabinet above the cards, said shoe having a body portion and a card carrying portion, means adjustably connecting the two portions of the shoe together so that the card engaging portion may be adjusted toward and from the cards, means operable from the exterior of the cabinet for bringing the shoe down against the upper edges of the cards and to move the shoe while in contact with the cards backward over the same to spread them by bending their upper edges backward, in succession, and spring actuated means to raise the shoe out of contact with the cards after the spreading operation and to return the shoe to starting position above the cards when the first mentioned means is released.

16. The combination with a file cabinet having a drawer therein adapted to contain file cards, one behind the other, and substantially upright, of a rod rockably supported in said cabinet above the cards and extending lengthwise of the drawer, a shoe above the cards and connected with said rod and adapted to be brought down against the cards in the rocking of the rod toward the same, a handle rotatably mounted on said drawer and operable from the exterior thereof, means connecting said handle with said rod in a manner permitting the drawer to be slid in the cabinet without rocking the rod and to enable the rod to be rocked by the handle to move the shoe into contact with the cards, and spring means to raise the shoe out of contact with the cards when the handle is released.

In testimony that I claim the foregoing as my invention, I affix my signature this 31st day of January, A. D. 1921.

PAUL E. FLEMING.
